(57) **CLAIM**

The ornamental design for a light, as shown and described.

DESCRIPTION

FIG. 1 is an isometric view of an embodiment of an ornamental design for a light according to the present invention;

FIG. 2 is a side view of the embodiment of an ornamental design for a light shown in FIG. 1;

FIG. 3 is a second side view of the embodiment of an ornamental design for a light shown in FIGS. 1 and 2;

FIG. 4 is a third side view of the embodiment of an ornamental design for a light shown in FIGS. 1, 2 and 3;

FIGS. 5 and 6 are end views of respective first and second ends of the embodiment of an ornamental design for a light shown in FIGS. 1, 2, 3 and 4;

FIG. 7 is a side view of an embodiment of an ornamental design for a light according to the present invention;

FIG. 8 is a second side view of the embodiment of an ornamental design for a light shown in FIG. 7;

FIG. 9 is a third side view of the embodiment of an ornamental design for a light shown in FIGS. 7 and 8; and,

FIGS. 10 and 11 are end views of respective first and second ends of the embodiment of an ornamental design for a light shown in FIGS. 7, 8 and 9.

Broken lines in the illustrations of FIGS. 7-11 of the drawing indicates parts of the article that are not part of the design illustrated therein.
